UNITED STATES PATENT OFFICE.

WARREN HILL, OF TOWANDA, PENNSYLVANIA, ASSIGNOR OF ONE-HALF
TO NORMAN P. HICKS, OF SAME PLACE.

CENTER-DRAFT MOWING-MACHINE.

SPECIFICATION forming part of Letters Patent No. 392,335, dated November 6, 1888.

Application filed July 7, 1886. Serial No. 207,329. (No model.)

To all whom it may concern:

Be it known that I, WARREN HILL, of Towanda, in the county of Bradford and State of Pennsylvania, have invented a new and Improved Center - Draft Mowing - Machine, of which the following is a full, clear, and exact description.

This invention relates to certain new and useful improvements in that class of mowing-machines provided with a central draft—that is, in which the horses travel in front of the cutter.

The object of my invention is to simplify the construction, avoid friction, and permit of adjusting the machine for different purposes.

The invention consists in the construction and combination of parts and details, as will be fully described and set forth hereinafter, and then pointed out particularly in the claims.

Reference is to be had to the accompanying drawings, forming a part of this specification, in which similar letters of reference indicate corresponding parts in all the figures.

Figure 1 is a plan view of my improved center-draft machine, parts being broken out and others in section. Fig. 2 is a side view of the same, parts being broken out. Fig. 3 is an enlarged detail plan view of one end of the cutter-bar, showing the mechanism for operating the cutter-bar. Fig. 4 is a cross-sectional view of the finger-bar. Fig. 5 is a sectional view of the ball-and-socket joint at one end of the angle-lever for operating the cutter-bar. Fig. 6 is a detail longitudinal sectional view of the ball-and-socket joint for adjusting the cutter-bar and shoe. Fig. 7 is a cross-sectional elevation of the same. Fig. 8 is a side elevation of one of the shoes. Fig. 9 is a cross-section of the same, and Fig. 10 is a side elevation of one of the "bridge-pieces."

The wheels A, which support the machine, are mounted loosely on the axle B, and are connected with the same by the usual ratchet-and-pawl mechanism, (not shown,) so that the axle B is rotated by the wheels A when the machine is drawn forward; but the wheels revolve freely on the axle when the machine is moved backward. The axle B carries a fixed cog-wheel, C, engaging with a pinion, C', mounted rigidly on the short shaft D', journaled in the gear-frame D, which is loosely

mounted on the axle B. Said pinion C' is provided with a clutch-collar, C², which engages with a clutch-collar, E', made integral or united with the cog-wheel E, mounted loosely on the shaft D' and provided with the annularly-grooved boss, E², with which engages the forked end of a lever, E, pivoted at its rear end to the gear-frame D. To the lever E³ is pivotally connected the elbow-shifting lever E⁴, guided at its angle between two cam-pieces, E⁵ E⁶, attached to the gear-frame D, and provided with a handle extending to within easy reach of the operator, so that when the lever is moved in the direction of the arrow a, the angle of the lever being free to slide between the cam-pieces E⁵, the lever will be moved inward in the direction of the arrow b, and thus move the lever E to the position shown in Fig. 1, and thereby throw the clutch of the gear-wheel into engagement with the clutch of the pinion C'. When the elbow-lever is moved in the reverse direction of the arrow a, the said lever will then be moved outward and the clutch of the gear-wheel E disengaged from the clutch of the pinion C'.
55 60 65 70 75

The cog-wheel E engages with the pinion F, loosely mounted on the axle B and made integral with the flanged wheel F', having the inner edge of its flange provided with cogs or teeth, which engage with the pinion F², mounted rigidly on a crank-shaft, G, which is journaled in the gear-frame D and in the end of an arm, D², of said frame, and on the end of said shaft G the disk G' is mounted, which is provided with a crank-pin, and with said pin the pitman-rod H is connected by a ball-and-socket joint. The other end of the pitman H is connected with the angle-lever I, pivoted to swing on the bolt I' on the rear part of the bridge-piece J³ on shoe J. The bridge-pieces J³ are provided with a side and end flange and have a stepped bottom, as clearly shown in Fig. 10. The angle-lever I is connected with the cutter-bar K.
80 85 90 95

The pitman H is connected with the angle-lever I by a ball-and-socket joint, which is shown in detail in Fig. 5. The end H' of the pitman H is forked to receive a socket-section, H², two of which sections form the socket for receiving the ball I² on the end of the rod I. A shackle or clevis, L, is passed around the

two socket-sections H^2 , and is held in place by a bolt, H^3 , passed through said shackle L and a slot in the pitman H . The forked end H' of the pitman H is provided with the bevels h , and the shackle L is provided on its end with the bevels h' , which fit snugly against the bevels h . In case the half-sockets of the ball become worn out, and it is desired to tighten them to prevent rattling, all that is necessary is to draw up the nuts on the bolt H^3 , for as the bevels h on the forked end H' of the pitman H work on the bevels h' on the ends of the shackle L the rounded or closed end of the shackle will be drawn toward the forked end of the pitman H at the same time that the ends of the shackle are drawn together, and thus the two half-sockets surrounding the ball are pressed more firmly together and form a complete socket. The operator can thus at any time adjust the joint in case the socket is too tight or too loose on the ball, and is thus enabled to adjust the machine to work perfectly.

In that end of the lever I opposite the one connected with the pitman H a slot, M , is formed, which has curved sides, the concaves facing each other, and in the slot a button, N , is placed, which has convex sides, is somewhat shorter than the slot M , and is mounted on a pivot, N' , on the end of the cutter-bar K . With this construction the circular motion of the end of the lever I transmits a reciprocating movement to the cutter-bar K , with but very little friction, the convex sides of the button rolling on the concaves of the slot, so that all sliding friction is avoided.

On each end of the axle B a V-shaped casting, O , is hung, which has the free ends of its arms connected by a curved brace, O' , and the downwardly-projecting arm of each casting O is provided with a longitudinal slot, O^2 , through which the bolt O^3 is passed, which holds the ends of the bars O^4 , which are secured to the draft-pole O^5 , thus permitting of adjusting the draft-pole higher or lower, as may be desired. In the ends of the forwardly-projecting arms of the castings O the ends of an arched bar, P , are held, which extends across from one casting to the other and is clamped by the lugs P' on the front end of the frame D , the ends of said arched bar P being held in the front arms of the castings O in the bottom edges of the lower ends of said arms. On the end of the front arm of each casting O a tube or rod, R , is held, which rods are slightly bent outward in front of the wheels, so as to increase the cutting width of the machine, and the front and lower ends of said rods or tubes R are inserted in sockets S , projecting upward toward the rear and slightly toward each other from the rear ends of the bridge-piece J^3 of the shoes. On the lower end of each tube or rod R a ball, R' , (see Fig. 6,) is formed, which fits against the seat R^2 , formed in the socket S , and is held loosely in place by a socket cap-piece, R^3 , held on the socket S by a bolt, R^4 , and a nut on said bolt. The socket-pieces S increase in diameter in one direction

toward their upper rear ends, as shown in Figs. 6 and 7, and in said rear ends the adjusting-screws S' are held, the inner ends of which rest against a collar, S^2 , surrounding loosely that rod or tube R inserted in the corresponding socket-piece. The bridge-pieces J^3 of the shoes J on opposite sides of the machine are united by the finger-bar T , which is secured to the bridge-pieces J^2 by bolts, as clearly shown in Figs. 3 and 10. The said bar T is inclined slightly from the front to the rear, as shown in Figs. 2 and 4, and on said finger-bar T the fingers T' are held by bolts T^2 . The cutter-bar K slides on the flat level portions T^3 of the fingers, slightly in front of the bar T , and each finger is provided in front of the cutter-bar with the laterally-projecting wings U . In the flat level portion T^3 of each finger T' an oil-cup, U' , is formed.

Each shoe J is provided with the laterally-projecting flanges V , the rear ends of which form shoulders V' , and each shoe J is provided with the standards J^4 and J^5 , to which the bridge-piece J^3 is secured by bolts V^2 , V^3 , said bridge-pieces supporting the finger-bar T , which does not connect the shoes directly, but connects them by means of said bridge-pieces, as stated above. The bridge-pieces can be adjusted higher or lower on the shoes, as may be desired, so as to bring the cutter-bar a greater or less distance from the ground. On the bolt which holds the bridge-piece on the rear standard of each shoe J a bar, V^2 , is pivoted, V^3 , which rests on the inner shoulder, V' , of the shoe, as clearly shown in Fig. 9, and is provided with a wing, V^4 , which wings serve to guide the cut grass, &c., toward the center of the machine.

The operation is as follows: The axle B is revolved from the wheels A , and by means of the cog-wheel C and the pinion C' the cog-wheel E is revolved when the clutch-collars C^2 and E^2 are engaged, and from said cog-wheel E the shaft G is revolved by means of the gearing within the frame D . By means of the pitman H the cutter-bar K is reciprocated. The finger-bar T is inclined toward the rear, thus causing the grass, &c., cut by the cutter-bar to slide down over the same very easily and rapidly. When the cutter-bar is inclined transversely from passing over uneven ground, the rods R being free to turn in the sockets S , the balls R' turning freely between the seats R^2 and socket cap-pieces R^3 , and the rods R in the collars S^2 , the cutter-bar will be free to follow the inequalities of the ground, so that it will rest evenly on the ground however inclined or uneven the surface may be.

The sockets S having wide mouths, they can be adjusted in relation to the rods or tubes R by means of the set-screws S' clamping the collars S^2 , so that the fingers T' can be inclined upward or downward, as desired.

The above-described machine is very compact and simple, cuts a very broad swath of grass, and all the parts of the machine can easily be so adjusted as not to rattle.

Having thus fully described my invention, I claim as new and desire to secure by Letters Patent—

1. In a center-draft mowing-machine, the combination, with the two shoes, of the vertically-adjustable bridge-pieces J^3 on the same, and provided with the sockets S , the rods R , passed into the sockets S and provided at their ends with balls fitting in the said sockets, the axle, wheels supporting the same, and frames on the ends of the axle, in which frames the upper ends of the rods R are held, substantially as herein shown and described. 35
  2. In a center-draft mowing-machine, the combination, with an axle, the wheels, and the frames on the ends of the axle, of the rods R , projecting from said frames and provided at their lower ends with balls and near their ends with the collars S^2 , the bridge-pieces J^3 , provided with the flaring sockets S , for receiving the balls on the ends of the rods R , the screws S' , bearing on the collar S^2 in the sockets for adjusting the sockets on the rods R , and shoes supporting the bridge-pieces, substantially as 20 herein shown and described. 40
  3. In a center-draft mowing-machine, the combination, with the shoes and a reciprocating cutter-bar, of a button mounted to turn on the top of said bar at one end, which button has its side edges rounded on a convex line, and of an angle-lever pivoted to the shoe and 25 45
- provided at one end with a slot having concaved sides, which slot receives the above-mentioned button on the cutter-bar, and of mechanism for rocking the angle-lever and reciprocating the cutter-bar, substantially as herein shown and described. 50
4. In a center-draft mowing-machine, the combination, with a rod having a forked end provided with bevels on the prongs, of a socket held against the forked end, a shackle surrounding the socket and provided with bevels on the ends of its prongs resting against the bevels on the prongs of the forked rod, and a bolt passed through the ends of the shackle and the forked end of the rod, substantially as herein shown and described. 55
  5. In a center-draft mowing-machine, the combination, with the wheels and axle, of a frame held on the axle, a train of gearing in said frame, clutch mechanism for throwing said gearing in and out of action, a pivoted forked lever engaging the clutch mechanism, an elbow shifting-lever connected with said forked lever, and the cam-pieces E^5 on the frame, between which the angle of the elbow shifting-lever is guided, substantially as specified. 55
